The ornamental design for a built-in coffee maker, as shown and described.

DESCRIPTION

FIG. 1 is a front perspective view of a built-in coffee maker according to our new ornamental design;

FIG. 2 is a front view thereof;

FIG. 3 is a top view thereof;

FIG. 4 is a right side view thereof, with the left side view thereof being a mirror image thereof;

FIG. 5 is a cross sectional view taken along lines 5-5 of FIG. 2; and,

FIG. 6 is a cross sectional view taken along lines 6-6 of FIG. 2.

The broken lines represent environment or structure of the built-in coffee maker and do not form any part of the claimed design.

The rear view of the built-in coffee maker is not ornamented and is therefore not shown.
